CLAIM

We claim the ornamental design for a telescopic sight mounting rack, as shown and described.

DESCRIPTION

FIG. 1 is a perspective view of a telescopic sight mounting rack with its environment of use on a telescopic sight shown in broken lines;

FIG. 2 is an objective end view thereof with its environment of use, including a telescopic sight and mounting clamps, shown in broken lines, the eyepiece end view (not shown) being identical;

FIG. 3 is a left side elevation view of the telescopic sight mounting rack of FIG. 1, the right side elevation view (not shown) being identical; and,

FIG. 4 is a bottom plan view of the telescopic sight mounting rack of FIG. 2.

The broken lines showing of the telescopic sight and mounting clamps in FIGS. 1-4 are illustrative of the environmental structure only and form no part of the claimed design.
